A. S. JOHNSON

SAFETY SIGNAL

Filed Sept. 6, 1921

132 Inventor:
Albert S. Johnson.

By James T. Burchell.

his Attorney.

UNITED STATES PATENT OFFICE.

ALBERT S. JOHNSON, OF OAKLAND, CALIFORNIA, ASSIGNOR TO THE FLASH-WAY CORPORATION, A CORPORATION OF CALIFORNIA.

SAFETY SIGNAL.

Application filed September 6, 1921. Serial No. 498,849.

This invention has to do with a safety signal and particularly with a hand signal of the general character set forth in my co-pending application entitled "Safety signal" filed May 26th, 1920, Serial No. 384,304, and it is an object of this invention to provide improvements in devices of this character to render them more useful, simple, convenient, and particularly effective.

10 A feature of the present invention is the provision of a device of the character specified which can be worn on the motorist's hand as a signal device and can be quickly converted into both a trouble light and into 15 a dash direction signal. This feature renders the device particularly convenient and also valuable commercially.

A particular feature of this invention is, 20 that the lamp proper is easily detachable from its carrier or lamp-box and having simple means provided to make it burn as a trouble light or the like, when independent of both its carrier and its flexure switch, thus adding usefulness and value to the device commercially.

Another noteworthy feature of the invention is the manner by which it illuminates the hand, which makes the signaling hand's position visible in the dark when at the 30 same time it throws signal lights both forward and backward transversely to the hand, but parallel to the path of direction to warn the oncoming motorists as well as those following of intended direction.

35 Still another feature of the invention is the simple interchangeable means provided for the convenience of the motorist to carry the lamp on the dash or steering wheel of the car from where it may be used as a 40 direction signal in a similar manner as when carried on the hand, except when so used it is operable by the thumb and forefinger instead of by flexure of the hand.

Another noteworthy feature of the invention 45 is the manner in which it illuminates the hand and at the same time throws signaling lights. The device when worn on the hand is controlled by movements of the hand and when one throws a light outwardly to illuminate the hand two signaling lights throw lights in opposite directions transversely of the hand.

Another feature of the invention is the novel means provided for permanently setting the device in the on or lighted condi-

tion. The invention provides a particularly simple, effective and easily manipulated means whereby the signal may be permanently set in the on or lighted condition.

The objects and features of this invention will be best and more fully understood from the following detailed description of a specific preferred form of the invention throughout which reference is had to the accompanying drawings in which:

Fig. 1 is a side elevation of the device showing it equipped with a wrist band; Fig. 2 is a plan view of the device shown in Fig. 1, being a view taken as indicated by line 2-2 of Fig. 1; Fig. 3 is an enlarged longitudinal detail sectional view, being a view taken as indicated by line 3-3 on Fig. 2; Fig. 4 is an enlarged detail transverse sectional view of the device, being a view taken as indicated by line 4-4 on Fig. 1; and Fig. 5 is a view similar to Fig. 1 showing the device equipped with a hook.

The device provided by the present invention comprises, generally, a body 10, an electrical connector 11 having connection with the inner end of the body 10, a switch or control device 12, and carrying means 13. The body 10 is a hollow member having an opening 14 at its outer end closed by a cover or lens 15 preferably of clear glass, or the like. On opposite sides the body is formed with openings 16 and 17 which are closed by covers or lenses 18 and 19 respectively, of different colored glass, or the like. For instance, in practice, one of said lenses may be colored green and the other red. At its inner end the body 10 is formed with an opening 20 which receives the electrical connector 11. In accordance with the preferred form of the invention the body 10 is formed of a solid or single piece of material and the lenses 15, 18 and 19 are held by rings 21, in the manner clearly illustrated in Fig. 3 of the drawings.

The electrical connector 11 comprises a cylindrical shell 22, an insulating block 23 carried in the shell, and other parts in connection with said shell and block. One end of the shell 22 is adapted to slidably fit in the inner end of the body 10 and is formed with a reduced part 25 provided with a screw threaded bore 26 adapted to carry an electric light bulb 27. A reflector 30 is carried on the reduced part 25 back of the bulb 27 to reflect light from the bulb outwardly.

through the opening 14. It will be noted, however, that the reflector does not prevent light from the bulb passing outwardly through the openings 16 and 17. Although the electrical connector is removable from the body 10 it is normally held in connection therewith by a pin 28 which extends from the shell to co-operate with a bayonet shaped slot 29 formed in the inner end portion of the body 10. The parts are shaped and proportioned so that the bulb 27 is opposite the openings 16 and 17 when the connector 11 is in its normal position in the body 10. The other end of the shell 22 is open to form a socket 37 for the reception of a plug 30.

The block 23 of insulating material, for instance, fibre or the like, is arranged in the middle portion of the shell 22 and carries two spaced metal carriers 31 in which are slidably carried contacts 32 and springs 33 which normally press the contacts 32 outwardly or toward the socket end of the electrical connector, as indicated by the arrows in Fig. 3. The carriers 31 have restricted parts 34 which cooperate with the enlarged inner ends 35 of the contacts to limit the outward movement of the contacts. A conductor 40 extends from one of the carriers 31 through the block 23 and connects with a compression spring 41 arranged between the block 23 and the restricted end part 25 of the shell 22. The spring 41 is adapted to be engaged by the contact 67 at the end of the base 42 of the electric light bulb 27 and operates to form an electrical connection between the conductor 40 and the contact 67, and also to hold the base 42 tight in the reduced part 25. An electrical conductor 46 extends radially outwardly from the other carrier 31 through the block 23 and through an insulating member 47 inserted in an opening 48 formed in the shell 22. The conductor 46 projects somewhat beyond the shell 24 as will be clearly seen from inspection of Figs. 1, 3 and 4 of the drawings.

The plug 30 comprises a block 50 of insulating material through which extends two electrical conductors 51. At the outer end of the plug the conductors 51 connect with wires 52 from a suitable source of electrical energy, say for instance, a battery 53, the arrangement of which will be herein-after described. At the inner end of the plug 30 the conductors 51 are formed with enlarged parts or heads 54 which are adapted to be engaged by the contacts 32 when the plug 30 is arranged in a certain predetermined position in the socket part of the shell 22. These parts may be of standard size and construction so that they can be easily replaced if necessary. The plug 30, although removable from the electrical connector, is normally held in the socket 37 of the elec-

trical connector by a pin 60 extending from the block 50 to co-operate with a slot or opening 61 in the socket forming portion of the shell. In accordance with the invention the opening 61 in the socket portion of the shell comprises a longitudinal part 62 through which the pin passes when the plug is being placed in or removed from the socket, and two oppositely extending transverse parts 63 at the inner end of the part 62 either of which is adapted to receive the pin 60. The parts are arranged and proportioned so that when the pin 60 is in place in one of the transverse parts 63 the contacts 32 engage and form electrical connections with the heads 54 of the conductor 51, while when it is arranged in the other transverse part 63 the contacts 32 are out of engagement with the heads 54 so that there is no electrical connection between the plug 30 and the electrical connector 11. The construction just described forms a switch by which the device may be conveniently thrown on or off, it being merely necessary to rotate the plug in the socket to cause the switching action.

The switch or control device 12, provided by the present invention, comprises a spring 65 extending inwardly from the under side of the body 10, and a contact 66 slidably carried on the spring 65 and adapted to engage and co-operate with the conductor 46 upon flexure or movement of the spring 65 in the direction indicated by the arrow in Figs. 1 and 3. When the contact 66 is in engagement with the conductor 46 a circuit is completed to the bulb 27 so that it burns or is lighted. The contact 67 at the end of the base 42 is connected with one of the wires 52 through the spring 41, conductor 40, one of the carriers 31, one of the contacts 32, and one of the conductors 51, while the outer part of the base 42 is connected with the other wire 52 through the shell 22, the body 10, the spring 65, the contact 66, the conductor 46, and the other carrier 31, the other contact 32, and the other conductor 51. When the contact 66 is not in engagement with the conductor 46 the last mentioned electrical connection is broken so that the circuit to the bulb is not complete. The contact 66 is slidable on the spring 65 so that it can be adjusted to various positions to vary the normal distance between it and the conductor 46 and thereby vary the amount of spring movement necessary to cause contacting of the contact 66 and conductor 46 in the manner above described. It will be obvious that the lamp can be turned permanently on or off by moving the contact 66 forward or back regardless of the position of the hand.

An arm 68 extends inwardly from the underside of the body 10 to a point about opposite the plug 30 and provides a member through which the above described parts of

the device can be connected with a wrist band 69 such as is shown in Figs. 1, 2, 3 and 4 or with a hook member 70^a such as is shown in Fig. 5. The member 75 to which the band 69 is attached is adapted to be detachably pivotally connected to the end of the arm 68 by a removable pivot pin 70. In the particular form of the invention now under consideration the band 69 is a resilient member and is in the form of an ended loop which can be placed around a person's wrist. At one side of the band 69 is provided a socket 72 for a lug 73 which extends from one side of the battery 53. The lug 73 co-operates with the socket 72 to removably attach the battery to the band 69. The member 75 is of such size and shape as to be engaged by the end of the spring 65 in the manner clearly illustrated in Figs. 1 and 3. When the band 69 is around a person's wrist the body part 10 of the device is at the back of the hand so that backward movement of the hand will cause the body of the lamp to pivot on its hinge 70 relative to band 69 in the direction indicated by the arrow in Fig. 1 and thereby cause flexure of the spring 65 which will cause contacting of the contact 66 with the conductor 46. Normally however, the spring 65 keeps the band 69 and body 10 against the hand with the contact 66 out of engagement with the conductor 46. When the body 10 is at the back of a person's hand and the switch device 12 is closed light passing through the opening 14 and lens 15 illuminates the fingers of the hand while the light passing through the openings 16 and 17 and the lens in connection therewith shines from the hand in directions transverse of the hand and in the plane of the hand.

When it is desired to use the device as a dash direction signal or when it is desired to use the device as a trouble light, the band 69 is removed by withdrawal of the pin 70 and the hook member 70^a is attached to the arm in place of the band 69. The hook member 70^a is a part which can be conveniently gripped by the hand and its other end can be arranged over various objects for the purpose of attaching the device thereto. The hook allows the device to be hung at any convenient place, say, on the dash, steering wheel, etc. When the hook 70^a is being used it is preferred that the source of electrical energy be a battery or generator which is not directly attached to the device but which is connected therewith by comparatively long wires, thus allowing the device to be easily handled and freely moved.

In accordance with the present invention a ring 80 is provided on the shell 22 at a point near the conductor 46, and a part 83 extends from the ring so that it can be moved into engagement with the conductor 46 upon proper rotation of the ring on the shell. When the ring has been rotated so that the

arm 83 engages the conductor 46 the circuit to the bulb 27 is completed through it rather than the contact 66 and the spring 65. It is only necessary to use the ring in the manner just described when the device is being used independent of or detached from the body of the signal as a trouble light, or at any time when it is desired that the bulb 27 be permanently lighted. Further, a thumb piece 90 is carried on a ring 91 which surrounds the outer portion of the plug 30 so that it extends rearwardly from the plug 30. The thumb-piece 90 presents a member which can be conveniently engaged by the thumb, when the hook 70^a is gripped by the forefinger, for the purpose of flexing the spring 65 to cause operation of the switch device 12 at a time when the device is being used as a dash signaling lamp and when the ring 80 is not set so that the electrical circuit is permanently closed.

When the device is mounted on a person's hand as above described and the person is driving a motor car the switch device is normally open, or in the position illustrated in Figs. 1 and 3 of the drawings, but automatically closes upon the hand being straightened out in the manner ordinary when giving a signal to other motorists. When the hand is straightened out in signaling position the body 10 of the device is raised somewhat back relative to the band 69 so that the switch device is closed thereby causing the bulb 27 to burn and throw light outwardly onto the fingers of the hand and from opposite sides of the hand. The light thrown on the fingers is preferably white and is for the purpose of illuminating the fingers so the signaling position of the hand will be clearly visible to other motorists as well as to pedestrians. The lights shining from the sides of the hand are of different colors to better denote direction of the course; for instance, the light of lens 18 showing to the rear may be red; and the light or lens 19 showing forward may be green or yellow; or whatever color best conforms to the established mode of signaling. This makes it possible for the motorist to make various signals by positioning the hand in various manners or to signal other motorists ahead of him and also other motorists behind him, simultaneously. For instance, to signal in the last mentioned manner the hand is held in a substantially horizontal plane so that one of the side lights, as the lights shining from the sides of the hand may be called, shines rearwardly while the other shines forwardly. When the device is being used as a trouble light the body 10 may be removed from the electrical connector, and therefore from around the light bulb 27, by manipulating the body and connector so that the pin 28 is disengaged from the slot 29.

Having described only a preferred form of

my invention I do not wish to limit myself to the specific details hereinabove set forth but wish to reserve to myself any variations that may fall within the scope of the following claims.

Having described a preferred form of my invention, I claim:

1. In a device of the character described, a body having an opening at its outer end and openings at opposite sides, lenses of different colors arranged at the last mentioned openings, illuminating means arranged in the body to throw light outwardly through all of the openings, said openings at opposite ends allowing light to shine transversely of a person's hand, and means in connection with the body for attaching it to a person's hand.
2. In a device of the character described, a body having an opening at its outer end and openings at opposite sides, lenses of different colors arranged at the last mentioned openings, single illuminating means arranged in the body to throw light outwardly through all of the openings, said openings at opposite ends allowing light to shine transversely of a person's hand, and means in connection with the body for attaching it to a person's hand.
3. In a device of the character described, a body adapted to be arranged at the back of a person's hand, illuminating means in the body, the body having an opening which allows light from the illuminating means to illuminate the fingers of the hand and openings which allow light to shine in directions transversely of the hand, means for causing said lights through the transverse openings to be different in color from that of the first mentioned opening, and means for mounting the body on a person's hand.
4. In a device of the character described, a body adapted to be arranged at the back of a person's hand, illuminating means in the body, the body having an opening which allows light from the illuminating means to illuminate the fingers of the hand and openings which allow light to shine in opposite directions transversely of the hand, means for causing said lights from said last named openings to be of different colors, and means for mounting the body on a person's hand.
5. In a device of the character described, a body adapted to be arranged at the back of a person's hand, illuminating means in the body, the body having an opening which allows light from the illuminating means to illuminate the fingers of the hand and openings which allow light to shine in opposite directions transversely of and in the plane of the hand, means for causing said lights from said last named openings to be of different colors and detachable means for mounting the body on a person's hand.
6. In a device of the character described,
7. In a device of the character described, a body adapted to be arranged at the back of a person's hand, illuminating means in the body, the body having an opening which allows light from the illuminating means to illuminate the fingers of the hand and openings which allow light to shine in opposite directions transversely of the hand, means for causing said lights from said last named openings to be of different colors, and means for mounting the body on a person's hand.
8. In a device of the character described, a body, an electric illuminant in the body, a mounting for the body comprising an attaching part pivotally connected to the body, and control means for the illuminant embodying a switch one of whose elements embodies a flexible member mounted at one end to move with the body and engaging the attaching part at its other end so as to be moved relative to the body when the body and attaching part are moved relatively.
9. In a device of the character described, a body, electric illuminating means in the body, mounting means for the body comprising an arm extending from the body and an attaching part pivotally connected to the arm, and control means for the illuminating means comprising a fixed contact on the body, a flexible member extending from the arm to said attaching part, and a contact on the flexible member and adapted to engage the fixed contact upon the flexible member being flexed due to relative movement between the attaching member and the arm.
10. In a device of the character described, a body, an electric illuminant in the body, a mounting for the body comprising an attaching part pivotally connected to the body, and control means for the illuminant embodying a switch one of whose elements embodies a flexible member mounted at one end to move with the body and engaging the attaching part at its other end so as to be moved relative to the body when the body and attaching part are moved relatively, and a contact member slidably on the flexible member and having its contact face inclined with respect to the other switch contact element.
11. In a device of the character described, an attaching part, a body and a member mov-

ably connecting the body to the attaching part, an illuminant in the body, and a control switch including a flexible member mounted between the body and the attaching part and adapted to be flexed by relative movement of the body and attaching part.

12. In a device of the character described an attaching part, a body movably connected to the attaching part, and an electric illuminant in the body, a controlling switch for the illuminant actuated by relative movement between the body and attaching part, and another switch means on the body operable independently of the first mentioned switch means to control said circuit.

13. In a device of the character described, an attaching part, a body, means for movably connecting said body to said attaching part,

and an electric illuminant in the body, a circuit for the illuminant including the body 20 and also an insulated contact member mounted on the body, a contact member, means for electrically connecting said contact member with the body and adapted to be moved into and out of engagement with the insulated 25 contact member by virtue of movement of the body relatively to the attaching part, and another contact member movably mounted upon the body and adapted to be moved into and out of engagement with the insulated 30 contact member.

In witness that I claim the foregoing I have hereunto subscribed my name this 27th day of August, 1921.

ALBERT S. JOHNSON.
